UNITED STATES PATENT OFFICE.

HENRY A. WEIHMAN, OF PHILADELPHIA, PENNSYLVANIA, ASSIGNOR TO
SIMONS BRO. & CO., OF SAME PLACE.

DESIGN FOR A BACK FOR A BRUSH OR HAND-MIRROR.

SPECIFICATION forming part of Design No. 21,629, dated June 21, 1892.

Application filed February 25, 1892. Serial No. 422,824. Term of patent 7 years.

To all whom it may concern:

Be it known that I, HENRY A. WEIHMAN, a citizen of the United States, residing at Philadelphia, in the county of Philadelphia and 5 State of Pennsylvania, have invented and produced a new and useful Design for the Backs of Brushes or Hand-Mirrors, of which the following is a specification, reference being had to the accompanying drawing, illustrating the design as applied to the back of a 10 brush or hand-mirror.

The leading feature of the design is a highly-ornamental scroll-pattern arranged about the edge of the back of the brush or 15 hand-mirror, with the inner portion of

the surface surrounded by said ornamental scroll pattern, plain or unornamented. The back may be furnished with a handle, as shown in the dotted lines in the drawing.

Having now described my design, what I claim as new, and desire to secure by Letters Patent, is—

The design for the backs of brushes and hand-mirrors, substantially as shown and described.

HENRY A. WEIHMAN.

In presence of—

ERNEST HOWARD HUNTER,
C. M. DIETTERICH.
